VACUUM FORMING PAPER MAKING
MACHINEEarl E. Berry, Beloit, Wis., assignor to Beloit Iron
Works, Beloit, Wis., a corporation of Wisconsin

Application September 9, 1935, Serial No. 39,679

7 Claims. (CL. 92—43)

This invention relates to a machine for making paper under the influence of suction. More specifically, this invention relates to a vacuum forming wet end for paper machines and includes a process for forming paper.

It has heretofore been proposed to form paper around suction rolls, evacuated cylinders and the like. These suction rolls and cylinders, however, have been rotated through, or partially 10 through a pond of stock to suck the fibers therefrom onto the forming surfaces on or around the rolls. In other words, the rolls and cylinders have been moved relative to the pond of stock. As a result, the paper formed on these machines 15 has the fibers thereof lying mostly in the direction of rotation of the cylinders. Furthermore, many of the fibers in the sheets so formed are up-ended, since they flow head-on against the forming surface. As a result, the paper is weak 20 longitudinally and tears readily along longitudinal lines. It also has a fuzzy surface due to the up-ended fibers therein.

To overcome these difficulties, I have now provided a forming part or wet end for paper making machines in which the paper stock moves or 25 travels with the forming surface so that little or no relative movement exists between the stock pond and the forming surface. Means are provided in the stock pond to prevent the fibers 30 therein from assuming a position parallel with the direction of flow.

In the machine of this invention the fibers are sucked from the moving pond onto the moving forming surface and are maintained in whatever hodge-podge arrangement they have assumed in the pond. The resulting sheet does 35 not have a grain or directional formation and the fibers therein are not upturned. The sheet is strong in both directions and free from fuzzy surfaces.

The principles of this invention can be carried out on both cylinder type paper machines and machines having an elongated traveling forming wire.

It is therefore an object of this invention to 45 provide a paper machine capable of producing paper free from fuzzy surfaces and from directional formation of fibers.

Another object of this invention is to provide 50 a paper machine having a forming pond traveling with a suction forming surface.

Another object of this invention is to provide 55 a vacuum forming paper machine for producing paper free from fuzziness and from grain formation of the fibers therein.

A further object of this invention is to provide a paper making machine with adjustable means for positively controlling the arrangement of fibers in the stock pond.

A further object of this invention is to provide 5 a process for making paper which is free from fuzzy surfaces and from grain formation of fibers.

Another object of this invention is to provide 10 a process for making paper in which fibers from a flowing pond of stock are deposited on a traveling forming surface moving with the flow of the stock pond.

Other and further objects of this invention will 15 be apparent from the following detailed descriptions of the annexed sheets of drawings, which illustrate preferred embodiments of this invention.

On the drawings:

Figure 1 is a side elevational view of the wet 20 end of a paper machine according to this invention, in which an elongated endless forming wire is used as the forming surface.

Figure 2 is an end elevational view of the apparatus shown in Figure 1.

Figure 3 is an enlarged, fragmentary, plan 25 view of the apparatus shown in Figures 1 and 2.

Figure 4 is an enlarged, cross-sectional view, taken substantially along the line IV—IV of Figure 2.

Figure 5 is a fragmentary cross-sectional view 30 taken substantially along the line V—V of Figure 4.

Figure 6 is a fragmentary side elevational view 35 of the mechanism for adjusting the width of the stock pond.

Figure 7 is an enlarged, vertical cross-sectional view of the suction roll and forming wire, illustrating in elevation the arrangement of fingers for preventing the fibers in the stock pond from 40 assuming a direction parallel to the flow of stock through the pond.

Figure 8 is an enlarged cross-sectional view, with a part in elevation, taken substantially along the line VIII—VIII of Figure 7.

Figure 9 is a cross-sectional view taken substantially along the line IX—IX of Figure 7.

Figure 10 is an end elevational view taken substantially along the line X—X of Figure 7.

Figure 11 is an enlarged horizontal cross-sectional view taken substantially along the line XI—XI of Figure 4, illustrating a stock overflow conduit for draining excess stock from the top of the stock pond.

Figure 12 is a cross-sectional view taken sub- 55

stantially along the line XII—XII of Figure 11, showing the adjustable drain for the overflow conduit.

Figure 13 is an enlarged elevational view taken substantially along the line XIII—XIII of Figure 4, illustrating the arrangement of pegs for preventing a directional flow of fibers into the stock pond.

Figure 14 is an enlarged, fragmentary, vertical cross-sectional view of the top portion of the suction roll used in this invention, showing the top suction area for sucking the fibers in sheet form onto the forming surface.

Figure 15 is an enlarged fragmentary view of the suction roll showing the lower suction forming area for initially depositing fibers from the forming pond onto the forming surface.

Figure 16 is a cross-sectional view taken substantially along the line XVI—XVI of Figure 14, showing an end of the suction roll with means for sliding the suction seal to vary the suction area.

Figure 17 is an end elevational view taken substantially along the line XVII—XVII of Figure 16.

Figure 18 is a diagrammatic view illustrating the manner in which the forming part or wet end of a paper machine according to this invention may be used on cylinder type paper machines wherein a pick-up felt receives the newly formed webs from the suction rolls.

Figure 19 is an enlarged fragmentary vertical cross-sectional view of one of the forming parts shown in Figure 18, illustrating the adjustable features for varying the width of the forming pond.

Figure 20 is a fragmentary plan view taken substantially along the line XX—XX of Figure 19.

As shown on the drawings:

In Figures 1 and 2, the reference numeral 10 indicates generally a suction roll, the construction of which will be more fully hereinafter described, having entrained therearound a water-pervious forming belt 11, such as, for example, a Fourdrinier wire. As shown in Figure 1, the belt 11 travels along its top run over guide rolls 12 and around a couch roll 13 in the direction indicated. The paper web W is removed from the belt 11 as it passes around the couch roll 13 and is received by a carrier band for passage through the rest of the machine not forming a part of this invention. The belt 11 along its under run passes under a guide roll 14 and then around the suction roll 10.

The suction roll 10 is rotatably mounted around a suction mandrel (hereinafter described) which mandrel is secured at its ends in a pair of end supports 15. An aqueous suspension of the paper stock is fed through feeder pipes 17 into a feed box 18, from which it flows through a forming pond, indicated at "P", having one side thereof bounded by the forming wire 11 as it passes around the suction roll 10. Fibers are sucked onto the forming belt 11 by the suction roll 10 and the flow of stock through the pond P is regulated to have the same speed as the peripheral speed of the suction roll 10 so that little or no relative movement occurs between the pond P and the suction roll. Excess stock from the pond P flows from the top of the suction roll 10 into drain pipes 19 located on each side of the apparatus.

The suction roll 10 is provided with three separate suction areas in which the amount of vacuum is separately regulated through pipe lines 20, 21 and 22 located on each side of the suction

roll. White water sucked into the suction roll is drained through large drain pipes 23 located on each end of the suction roll. The pipes 20, 21 and 22 have valves 24, 25 and 26 therein to control the amount of suction applied to each of the three suction areas of the suction roll 10. The pipes 20, 21 and 22 may be connected with a single vacuum pump or with separate vacuum pumps.

As best shown in Figure 4, stock entering into the feed box 18 from the feed pipes 17 passes around horizontal baffles 27 and 28, over a vertical baffle 29 and under another vertical baffle 30. A perforated flow-evener roll 31 is provided in the path of the stock below the baffle 30 to insure a quiet flow of stock into the pond P.

A shower pipe 16 directs a spray of water against the forming belt 11 as it enters into the pond P to wash the belt and to also prevent leakage of stock from the pond.

The feed box 18, as shown in Figure 4, is defined by a rear wall 32, side walls composed of the frame plates 33, and a rigid L-shaped member 38 having a vertical leg forming the baffle 30 and a horizontal leg carried on tracks secured to the frame plate 33. The L-shaped member 38 pivotally supports an arcuate shaped flexible metal plate 39 which is pivoted thereto as at 40.

The horizontal leg of the L-shaped member 38 carries a support 36 in which is slidably mounted a bolt 35 engaging the rear wall 32. A boss 34, threaded on the bolt 35, can be manually turned to effect relative movement between the L-shaped members 38 and the rear wall 32.

In this manner, the width or capacity of the feed-box 18, which receives stock from the pipe 17, may be varied as desired, depending upon the consistency of the stock, the speed of operation of the machine and the like.

As the stock flows from the feed-box 18 into the pond P, it travels around a plurality of pegs 37, best shown in Figures 4 and 13. The pegs are arranged in staggered relation and aid in preventing the stock fibers from assuming a direction parallel to the flow of the stock.

The arcuate member 39 has bolted on the top end thereof a V-shaped plate 41 having one side thereof curved with the plate 39 and the other side thereof bent outward at the end to form a horizontal leg 42 and a vertical leg 43. The end of the V-shaped leg 41 is pivotally secured at points 44 to a plurality of vertical rods 45. The rods 45 are spaced along the entire length of the plate 41, as indicated in Figures 3 and 5.

The rods 45 are slidable through supports 46 and 47 carried by a channel beam 48. The supports 47 are yoked as shown, and the ends of the rods 45 are slidable therethrough. Bosses 49 are threaded onto the ends of the rods 45 between the fingers of the supports 47. A rotation of the bosses 49 against the fingers of the supports 47 therefore effects a vertical movement of the rods 45 to adjust the end of the plate 41. Since the plate 41 may be flexible, a plurality of these rods are used to maintain a desired spacing of the end of the plate 41 from the forming band 11.

The channel beam 48 is secured at the ends thereof to the vertical legs of angle members such as 50 by bolts 51 extending through vertical slots 52 in the web of the channel beam and secured at their ends in the vertical leg of the angle member 50. Brackets 53 are secured to the ends of the channel beam 48 at the top thereof and the brackets 53 have rods 54 threaded therethrough and engaging at the ends thereof.

the top of the angle member 50. Turning handles 55 are secured to the rods 54 to facilitate manual rotation of the rod. Bosses 552 are also threaded around the rods 54 to bear against the supports 53 and lock the rods against rotation.

This construction permits a vertical sliding of the channel beam 48 along the vertical legs of the angle members 50 to vary the space between the plate 41 and forming band 11 without disturbing the adjustments of the rods 45 which holds the plate in parallel position to the forming band 11. If desired, of course, the rods 45 may be adjusted so as to flex the plate to provide a wider space between the forming wire and the plate at the ends of the plate or at the center of the plate, as desired.

The horizontal legs of the angle members 50 are slideable in grooved tracks formed in the horizontal portions 56 of supporting arms 57 which are positioned outside of the frame plates 33 and are pivoted to these plates 33 at points in alignment with the pivot point 40 of the arcuate plate 39. The arms 57 carry bosses 58 through which bolts 59 are rotatably mounted. The ends of the bolts 59 are threaded into nuts 60 carried by the angle members 50. A rotation of the bolts 59 therefore effects a horizontal sliding of the members 50 along the portions 56 of the arms 57.

As shown in Figures 3, 4 and 6, the side frame plates 33 of the structure have brackets 61 secured thereon in which are pivoted lever arms 62. The lever arms 62 in turn have pivoted thereon, at 63, links 64 which are adjustable in length and secured at their other ends to saddle members 65 pivoted to the arms 57 at 66.

A manual moving of the lever arms 62, shown in a solid line in Figure 6, to the position shown in dotted lines in Figure 6, throws the arms 57 from the position shown in a solid line to the position shown in dotted lines, thereby moving the entire structure supported by the arms 57 away from the forming band 11.

From the above description, it should be readily understood that the arcuate member 39 is pivoted about the points 40 and adjusted by means of the rods 54 and 45 into the desired position in spaced relation from the forming band 11. The angle members 50 are likewise slideable horizontally and serve to space the member 41 in proper position from the forming band 11. However, when it is desired to move the entire mechanism for cleaning the machine and for other purposes, a mere manual throwing of the levers 62, located on each side of the apparatus, moves the entire mechanism as a unit about pivot points without disturbing the adjustments made by the rods 45 and 54 and the bolts 59.

The arms 57 are locked in operative position by locking pins, such as 67 (Figure 4) each extending through an arm and a frame plate 33.

The arcuate plate 39, as shown in Figures 4, 7 and 8, has formed thereon a plurality of bosses 68 for receiving chucks 69 therethrough. The chucks 69 carry the shanks 70 of hoe-shaped fingers 71. As shown in Figure 8, the shanks 70 are provided with an elongated slot 72 intermediate their ends for receiving therethrough a pin 73 to lock the fingers against rotation relative to the chucks 69. The ends of the shanks 70 are preferably threaded as at 74 to space the fingers 71 a proper distance from the plate 39. To obtain the correct spacing, the pin 73 is withdrawn and the fingers 71 are threaded a proper distance into the chucks 69.

Worm gears 75 are secured around the chucks 69 in abutting relation to the bosses 68 by means of set screws 76 (Figure 8). The set screws 76 extend through the chucks 69 and may be clamped against the threaded end 74 of the shanks 70 to further hold the shank.

As shown in Figures 7 and 8, the ends of the chucks 69 are closed and provided with a square or polygonal head portion 77 for a purpose to be hereinafter described.

The arcuate plate 39 also carries near each end thereof, at right angles thereto, a supporting plate 78, which plates 78 have rotatably mounted therein a plurality of worm shafts 79 for engaging the worm gears 75. As shown in Figures 7 and 9, each of the worm shafts 79 engages with a plurality of worm gears 75 on each side thereof. Thus, one worm shaft 79 serves to engage two adjacent rows of worm gears 75. As shown in Figure 9, at least one end of each worm shaft 79 is provided with a square or polygonal well 80 adapted to register with slots 81 formed in the side plate 33 of the frame structure. A wrench can thus be inserted through the slots 81 of the side plate 33 to rotate the worm shafts 79 and thereby adjust the fingers 71 into a desired position.

As shown in Figure 10, a rotation of a worm shaft 79 will position one row of fingers 71 in one direction, while the adjacent row of fingers will be moved in the opposite direction. The fingers 71, as shown in Figure 10, are streamlined and serve to deflect the flow of fibers through the pond P to prevent a parallel arrangement of fibers in the pond. Each finger creates an eddy current in the flow of the stock and aids to maintain the fibers in a hodge-podge condition.

When it is desired to adjust one or more of the fingers 71 relative to the other fingers in the same row, the set screw 76 (Figure 8) may be removed and the end 77 of the chuck 69 engaged by a wrench to rotate the chuck thereby rotating the finger 71 into the desired position. At the same time, since the screw 76 is removed, the gear 75 is not turned to effect a rotation of the worm shaft 79. After the individual adjustment of a finger 71 according to this method, the screw 76 is reinserted and the adjusted finger 71 will then be rotated with a rotation of its worm gear 79. This construction thereby permits an adjusting of the fingers 71 individually and together as units of adjacent rows. This arrangement efficiently serves to prevent grain formation of fibers in the sheets being formed since it can be readily adjusted for all types of stock flowing through the pond P and for all speeds of the machine.

Stock from the feed box 18 flows through the pond P wherein the fibers are maintained in hodge-podge relation by the directing fingers 71 so that they are deposited on the forming band 11 to form a well matted sheet with the fibers laying in all directions. The excess stock flows around the V-shaped plate 41 over the horizontal leg 42 thereof and through openings 82 (Figures 4 and 11) located on each side of the machine. The openings 82 are cut through the side frame plates 33 of the machine. The vertical leg 43 of the plate 41 directs the stock through the openings 82. Conduits 83 communicate with the openings 82 and direct the excess stock into the return pipe 19 (Figure 2).

As best shown in Figures 11 and 12, the conduits 83 are provided at a point over the return pipe 19

pipe 19 with an inturned annular flange 84. A cylinder 85 is slidably mounted in the opening formed by the flange 84. A supporting bar 86 extends across the top of each conduit 83 and a threaded rod 87 extends through the support 86. The rod 87 is provided with a hand wheel 88 on the top end thereof. A bracket 89 is secured across the interior of the cylinder 85 and receives the threaded end of the rod 87 therethrough. A nut 90 is threaded onto the rod 87 beneath the bracket 89 so that when the rod is rotated the cylinder is raised and lowered in the annular opening defined by the flange 84. The stock flowing through the conduit 83 must flow over the top of the cylinder 85 therein to be directed therethrough into the return pipe 19. The cylinders, however, can be raised and lowered to vary the level of the stock in the conduit 83, thereby effecting a positive control of the stock maintained in the conduit 83 and on the top of the suction roll 10.

The return pipes 19 may be connected with a mixing box to direct the overflow stock therein for admixture with fresh stock. This admixture can be fed back to the feed box 18 through the pipes 17.

The side plates 33 of the frame structure of the machine have portions 91 extending over the suction roll 10. (Fig. 4.) Each portion 91 carries a plate 92 hooked over the top thereof as at 92a, best shown in Figure 5. One side of the plate 92 has an inturned flange 92b for a purpose to be hereinafter described. Each plate 92 is provided with a pair of elongated slots 93 for receiving bolts 94 therethrough. The bolts 94 are secured in the portions 91 of the plates 33.

The plates 92 also carry bosses 95 which have bolts 96 threaded therethrough. The portions 91 of the plates 33 have secured thereon saddles 97 for receiving the ends of the bolts 96 therethrough. A loosening of the bolts 96 and a rotation of the bolts 96 effects a horizontal sliding of the plates 92 along the portions 91 of the frame. The portion 92a of each plate 92 maintains the plate on the portion 91.

A slice plate 98 having a horizontal flange portion 99 at right angles thereto abuts the portions 92b of the plates 92 and extends across the entire width between the portions 91 of the frame plates 33. As best shown in Figure 5, a rod 100 extends through the flange 99 of the plate 98 and contacts at its end the portion 92a of the plate 92. A hand wheel 101 is provided at the other end of the rod 100 for manual rotation of the rod. A boss 102 provided with a handle for manual gripping is threaded onto the rod and disposed over the flange 99 of the plate 98. Since the rod 100 is threaded through the flange 99 it follows that the plate 98 may be raised and lowered relative to the side frames to effect a proper spacing of the bottom of the plate from the forming band 11, by a loosening of the boss 102 away from the flange 99 of the plate 98 and a rotation of the rod 100 to either raise or lower the plate 98 from the portion 92a of the plate 92. When it is desired to lock the plate 98 in position, the boss 102 is clamped down against the flange 99. This arrangement is identical with the arrangement of the rod 54 and the handles 55 and 55a thereof for regulating the position of the channel member 48 relative to the angle plate 50. The flanges 92b of the plate 92 serve as supports for the plate 98. Since the stock flows against the plate 98, the plate will be forced outwardly against the flanges 92b, thereby preventing a leaking of the stock.

As shown in Figure 5, the plate 98 has a plurality of brackets 103 secured near the bottom thereof. Rods 104 extend through the brackets 103 and carry at their ends a flexible slice strip 105 which extends below the bottom of the slice plate 98. The other ends of the rods 104 are freely rotatable in chucks 106 which are externally threaded into the flange 99 of the slice plate 98. Handles 107 are provided for rotating the chucks 106 to raise and lower the same relative to the flange 99, thereby raising and lowering the rods 104 to adjust the strip 105 into the desired spacing from the forming band 11. Since the rods are freely rotatable within the chucks, they are not rotated with the chucks, and as shown in Figure 4, the strip 105 is secured in notches in the ends of the rods 104, thereby holding the same against rotation with the chucks. This arrangement provides for a micrometer adjustment of the spacing of the strip 105 from the forming band 11. Since the strip 105 is flexible, preferably being formed of a flexible material, such as a rubber composition or a flexible metal strip, the spacing can be varied as desired along the length of the strip 105. The rods 100 serve to space the slice plate 98 relative to the forming band, while the rods 104 move the slice strip 105 relative to the slice plate 98, thereby providing an added micrometer adjustment for the slice.

The slice is, as described above, therefore adjustable both in a horizontal and vertical direction relative to the forming band 11.

As shown in Figure 5, the portions 91 of the plates 33 abut the forming band 11 and act as end dams for the pond of stock flowing into the opening 82. The slice plate 98 acts as a front wall for this pond, while, as pointed out above, the vertical leg 43 of the V-shaped strip 41 serves as the other side wall.

As pointed out in Figure 1, the suction roll is rotatable around a suction head mandrel which is secured at its ends in the end supports 15. As shown in Figure 5, the suction mandrel 108 is bolted by bolts 109 into the annular recess defined by the flanges 15a of the end supports 15.

The mandrel 108 is provided with three rows of openings 110, 111, and 112 disposed along one side thereof toward the stock pond P, as shown in Figure 4. Partition walls 113 and 114 are provided in the mandrel to define three separate chambers 115, 116 and 117 therein, each communicating with a separate row of openings 110, 111 and 112. The end supports 15 for the mandrel 108 are likewise provided with partitions 118 and 119 (Figure 4) to define three separate passageways 120, 121 and 122, respectively, communicating with the passageways 117, 116 and 115, respectively. The passageways 120, 121 and 122 of each end support 15 are connected with pipes 123, 124 and 125, respectively, for receiving the white water drained into the passageways. This white water may be used for diluting the stock in a mixing box for feeding back to the feed box 18.

Each passageway 120, 121 and 122 is provided with a baffle 126, 127 and 128, respectively, which as shown at 127 in Figure 5, extends above the normal flow of water from the mandrel 108 and is in spaced relation from the supports 15. The suction pipes 20, 21 and 22 open into the passageways 120, 121, and 122 behind the baffles in these passageways, as shown in Figure 5. The white water therefore flows through the passageways into the pipes 123, 124 and 125, while air is sucked through the openings 110, 111 and 112 in the mandrel and flows behind the baffles into

the suction pipes 20, 21 and 22. By this arrangement, a very high vacuum can be obtained and the degree of vacuum can be separately regulated in each of the three passageways in the supports and mandrel. The drain pipes 123, 124 and 125 may also be connected with pumps to effect a forced draining of the white water from the mandrel.

The perforated suction roll 10 is bolted at one end thereof, as shown in Figure 5, to a large gear 129 having a chime ring portion 130 integral therewith for spacing the roll 10 from the mandrel 108. The roll 10 sets over the ring 130 while the mandrel fits within the ring 130. A bearing sleeve 131 is secured around the mandrel 108 by means of pins 132, as shown in Figure 5. A bronze bearing ring 133 is tightly fitted around the sleeve 131. The ring 133 has an outturned flange at one end thereof as shown. An end thrust ring 134 is secured around the mandrel 108 to abut the flange of the bearing ring 133. The chime ring 130 and the gear 129 thus slide over the bearing 133. The other end of the perforated roll 10 is mounted in an identical manner on a chime ring 130, but only one gear 129 is used. The gear 129 engages with any suitable source of driving power and the cylinder 10 is therefore rotated around the mandrel 108.

On each side of each row of openings 110, 111 and 112 in the mandrel 108, there are formed on the mandrel outturned flanges 135, 136, 137 and 138, as shown in Figure 4. The flanges 135 and 137 have bolted thereon angle members 139 and 140, respectively, which carry sealing strips 139a and 140a, respectively, in their vertical legs for rubbing against the interior of the roll 10. The horizontal leg of the angle member 139 may be slotted as shown at 141 in Figure 14 for receiving the bolts 142 therethrough. The member 139 can thus be slid along the slot 141 to adjust the position of the strip 139a. This adjustment, however, can only be made when the mandrel 108 is removed from the perforated roll 10.

In the event it is desired to vary the suction areas along the roll 10 without removing the mandrel from the roll, the flanges 136 and 138 carry angle members 143 and 144, respectively, which are adjustable from outside of the roll 10, as will be hereinafter described. The angle members 143 and 144 have vertical legs carrying sealing strips 143a and 144a, respectively, which rub against the interior of the roll 10. The horizontal portions of the angle members 143 and 144 which are curved to fit on the flanges 136 and 138, respectively, are provided with slots 145 and 146, respectively, best shown in Figures 14 and 15. Bolts 147 and 148 extend through the slots 145 and 146 and are threaded into the flanges 136 and 138 respectively. Coiled springs 149 and 150 are disposed around the bolts 147 and 148, respectively, and held under compression between the heads of these bolts and washers 151 and 152 respectively, which washers are disposed around these bolts and fit over the horizontally curved portions of the angle members 143 and 144, respectively. The angle members 143 and 144 are thus held tightly against the flanges 136 and 138, respectively, but are adapted to be slid along these flanges because of the spring retaining means.

The sealing strips 139a, 143a, 140a and 144a, define three separate suction areas against the roll 10. The ends of these areas are sealed by annular sealing strips 153, best shown in Figure 5, carried by an annular member 154 which is bolted

to the mandrel 108 by bolts 155 extending through an outturned flange 156 snugly fitted around the mandrel 108, as shown in Figure 4. It should be understood that a flange ring 156 is positioned near each end of the mandrel 108 and each ring 156 has bolted thereon an annular member 154 carrying a sealing ring 153 which rubs against the inside periphery of the roll 10 at each end thereof. The three separate suction areas are therefore sealed both at the sides and at the ends.

As shown in Figures 16 and 17, the mandrel 108 has formed thereon a pair of supports 160 and 161 spaced from each other opposite the angle member 143, but outside of the end sealing ring 154. A similar pair of supports is formed opposite the angle member 144. As shown in Figure 17, the supports 160 and 161 extend through the horizontal leg of the sealing member 154 and receive therebetween a horizontal bolt 162 which is rotatably mounted at its ends in the supports. The bolt is provided with a head 163 adapted to be engaged by a wrench for rotation. The bolt 162 has a boss 164 threaded thereon. The boss 164 carries a rod 165 projecting through a slot 166 formed in the vertical portion of the sealing member 15. The rod 165 extends into a well 167 formed in the angle member 153 and is secured therein by means of a pin 168.

As shown in Figures 16 and 17, the chime ring 130 is provided with an opening 169 which may be covered by a cover plate 170. Removal of the cover plate 170 makes it possible to insert a wrench for engagement with the head 163 of the bolt 162. Rotation of this bolt moves the boss 164 along the bolt to thereby slide the angle member 143 along the flange 136. An identical apparatus is provided to move the angle member 144. In this manner, the suction areas defined by the sealing strips 143a and 144a may be varied without removing the mandrel 108 from the roll 10.

The devices for moving the angle member 143 and 144 can be mounted adjacent the chime ring 130 which is at an end of the roll 10 away from the gear 129, since more room is provided at this end of the roll 10. It is obvious, however, that the opening 169 shown in Figures 16 and 17 could extend through the gear 129 as well as through the chime ring 130.

The above description illustrates the principles of this invention as applied to machines using an elongated traveling forming band which rotates around the suction cylinder. The principles of the invention are also adapted to cylinder type paper machines wherein the fibrous webs are formed on rotating cylinders and removed therefrom by a pick-up felt. The following description shows the adaptation of the principles of this invention to cylinder type paper machines.

In Figure 18, the reference numerals 180 indicate generally foraminous cylinder molds having therein the same type of suction mandrel described above. These molds 180 rotate through forming ponds within the housings 181. The housings 181 are similar to the structure defined above, and the forming pond therein travels with the cylinder molds. A pick-up felt 182 is trained over the tops of the cylinder molds 180 and pressed thereagainst by couch rolls 183 for receiving the fibrous webs formed on the cylinder molds. The pick-up felt is trained around guide rolls 184, as shown. The fibrous web W is re-

moved from the pick-up felt after it passes over the last cylinder mold 180 and deposited on a carrier 185 for further treatment.

As shown in Figure 19, the suction roll 180 rotates through the flowing pond P in the same manner in which the suction roll 10 rotates through the pond described in Figure 4. However, a screen forming wire 180a is integrally secured around the roll 180 instead of traveling therearound as the belt 11 described above. An arcuate plate 186 is pivotally mounted in the same manner in which the arcuate plate 39 described in Figure 4 is mounted, and carries a plurality of fingers 187 in the same manner in which the fingers 71 are carried by the plate 39. Worm shafts 188 are rotatably mounted at their ends in plates 189 carried by the arcuate member 186 at right angles thereto at each end of the arcuate plate. The arcuate plate 186 has formed integrally thereon a portion 190 bent back therefrom, as shown in Figure 19. This portion 190 also carries a leg portion 191 therebeneath. The end of the leg portion 191 is disposed over a trough 192 which extends across the entire width of the machine between the frame plates 181, and is supported by the frame plates. The pond P then thereby flows over the portion 190 of the plate 186, over the leg 191 and into the trough 192. It is drained from the trough 192 by drain conduits, such as 193 located on both sides of the machine outside of the frame plates 181.

An arm 194 is pivotally mounted on each side of the machine outside of the frame plates 181 at points in alignment with the point at which the arcuate plate 186 is pivoted. These arms are therefore mounted in the same manner in which the arms 57 are mounted, as shown in Figures 4 and 6. The arms 194 each have a flat horizontal top portion 195, best shown in Figure 20. The portions 195 of the arms carry brackets 196 and have plates 197 slidably mounted thereon. The plates 197 are integrally connected with a top plate 198 which extends across the entire top of the apparatus, being carried at each end by the plates 197.

Each plate 197 has a raised housing 199 formed on the top thereof having a threaded well therein for receiving a bolt 200. The bolt 200 is rotatably mounted within the bracket 196, and a rotation of this bolt by a handle 201 secured thereon slides the plate 197 to thereby move the depending top plate 198. The top plate 198 carries a flexible slice strip 202 at one end thereof which extends across the periphery of the cylinder 180 in adjustable spaced relation therefrom. The end of the slice strip 202 carries a plurality of vertical brackets 203, in which are pivoted a plurality of rods 204. The top plate 198 also carries a plurality of brackets 205 in horizontal alignment with the brackets 203 so that the rods 204 can extend therethrough. The rods 204 are also pivoted in the brackets 205.

The ends of the rods 204 are yoked, as at 206. Bolts 207 extend through the yoked portions 206 of the rods and are urged at their ends against the top plate 198. Nuts 208 are threaded around the bolts 207 between the bifurcated fingers of the yoked portion 206. A manual setting of the bolts 207 by the nuts 208 thereby effects a vertical adjustment of the slice strip 202. Since this strip is of a flexible nature the adjustments can be varied across the length of the strip by a manual setting of the different rods 204. This arrangement provides a micrometer adjustment 75 along the entire length of the strip to accurately

space the same a desired distance from the cylinder 180. Rough adjustments can be made by sliding the plates 197 on the arms 194 to move the top plate 198 toward and away from the cylinder 180.

The top plate 198 has a vertically extending flange 209 formed at the back end thereof through which bolts, such as 210, extend. An L-shaped member 211 extending across the full length of the plate 198 is carried by the plate 198 adjacent to the flange 209 thereof by means of bolts, such as 212, which extend through slots, such as 213, formed in the top plate.

The ends of the bolts 210 are threaded into the angle member 211, and when the bolts 212 are loosened, the angle member may be slid along the plate 198 by a rotation of the bolts 210 to thereby vary the gap between the vertical leg of the angle member and the end of the plate portion 190. This arrangement provides an adjustable weir for the flow of stock into the trough 192.

The side flange plates 181 are provided with elongated slots 214 for receiving lugs 215 carried by the arms 194. The lugs 215 extend through the plates 189 so that when the arms 194 are moved, the arcuate plate 186 and its appended mechanisms are moved with the arms.

Mechanism for moving the arms comprises a rod 216 pivotally mounted at one end, as at 217, 30 to each arm 194 outside of the frame plates 181. Each rod 216 is secured at the other end in a curved member 218 which is pivoted at 219 to a lever arm 220. The lever arm 220 in turn is pivoted at its end in a bracket 221 carried by the 35 frame structure of the machine. When the lever arm 220 is rotated manually about its pivot point the member 218 moves the rod 216 back to thereby rotate the arms 194 about their pivot points. The arcuate plate 186 and the top plate 198, 40 together with their appended mechanisms, are all moved with the arms 194. This permits an opening of the machine for inspection and for cleaning. A stop pin 222 may extend from the side plates 181 for preventing the lever arm 220 45 from dropping below a desired point. Thus, a rotation of the lever arm 220 against the stop pin 222 moves all of the structure carried by the lever arm into operative position adjacent the cylinder 180.

As shown in Figure 20, the cylinder 180 extends beyond the side frame plates 181 and has a gear 223 secured therearound for driving the cylinder.

The suction mandrel structure of the cylinder roll 180 is identical with the structure defined in 55 Figures 4 and 5.

From the above description, it should be understood that the invention comprises wet ends for paper machines of either the cylinder type or the type using Fourdrinier forming wires. In 60 the operation of these machines, an aqueous suspension of stock flows from a feed box upward through a forming pond, one side of which is defined by the suction roll which may either carry a forming surface or may have the forming surface integral therewith. The suction roll has three separately controlled suction areas. Upon entering the forming pond, the stock is subjected to a low degree of suction from the first suction area to effect initial formation of fibers 70 on the forming surface. The fibers thus deposited on the forming wires then are subjected to the action of a higher degree of suction from the next suction area. At this point additional fibers are also deposited on the initial fiber for- 75

mation to complete the formation of the sheet. As the formed sheet then travels along the forming surface, it is subjected to a third suction treatment wherein the fibers are sucked onto the 5 forming wire into sheet form. Very little additional deposition of fibers occurs in the third suction area, but the fibers deposited from the two preceding suction areas are set into their final position in the fibrous mat.

10 The forming surface with the matted fibers thereon then passes under a slice which acts as a dam to prevent flow of stock over the top of the forming surface along its top run. Suction may be applied through the forming surface beyond 15 the slice for draining water from any stock which passes beyond the slice. The excess stock from the forming pond flows upwardly behind the slice and is drained back into a mixing box where it may be admixed with fresh stock for 20 feeding back to the feed box of the machine.

The apparatus provides for the moving of the forming pond together with the forming surface so that no relative movement occurs between the forming surface and the fibers in the forming 25 pond as the fibers are being deposited on the forming surface. The flowing of the stock upwardly, rather than the usual downward flow, provides for a more positive control of the flow in the forming pond and produces a quiescent 30 flow which could not be obtained through a gravity downward flow. The fibers are thus traveling in the same direction as the forming surface and travel at a controlled speed, preferably the same speed as the forming surface. 35 Means are provided in the forming pond, however, for maintaining the fibers in a hodge-podge relationship to prevent a grain formation in the fibrous sheet being produced.

All parts of the machine are capable of being 40 accurately adjusted to obtain optimum operating conditions.

I am aware that many changes may be made and numerous details of construction may be varied through a wide range without departing 45 from the principles of this invention, and I, therefore, do not purpose limiting the patent granted hereon otherwise than is necessitated by the prior art.

I claim as my invention:

50 1. A wet end for paper machines comprising a suction roll rotatably mounted in a frame structure, a forming wire around said roll, a feed box adjacent the bottom of said suction roll, an arcuate plate extending around a portion of said suction roll and pivotally mounted on said feed box, means for variably spacing said plate from said suction roll, a plurality of rods extending thru said plate toward the forming wire, enlarged fingers on the ends of said rods extending transversely therefrom, means for rotating said rods about their own axis to position the fingers, means for flowing stock from said feed box through the space between said plate and said suction roll for deposition of fibers on the forming wire around 55 said roll, a slice in spaced relation from the end of said arcuate plate, means for adjustably spacing said slice from said forming wire, means for maintaining a head of stock above said plate, and means for removing excess stock from said head.

70 2. In a paper machine, a pair of side frame plates in spaced relation, a feed box formed between said plates at the bottom thereof, an arcuate member pivoted at one end above said feed box, a suction roll in spaced relation from said arcuate member, said suction roll, side plates and

arcuate member together defining a passageway for paper stock from said feed box, said arcuate member having turned-back flanges on each side thereof abutting said side plates, worm shafts extending across the width of said arcuate member and rotatably mounted at their ends in said flanges, a plurality of rows of hoe-shaped fingers rotatably mounted in said arcuate member and extending into said passageway, worm gears operatively connected to said fingers for engagement with said worm shafts, and openings in said side plates adjacent the ends of said worm shafts to permit a rotation of the worm shafts for adjusting the position of said fingers in the passageway. 15

3. In a paper machine, a pair of side frame plates in spaced relation, a feed box formed between said plates at the bottom thereof, an arcuate member pivoted above said feed box, a suction roll in spaced relation from said arcuate 20 member, said suction roll, side plates and arcuate member together defining a passageway for stock from said feed box, a V-shaped member secured to the end of said arcuate member, rods pivoted at the end of said V-shaped member, a pair of arms pivotally mounted outside of said frame plates, a support for said rods slidably mounted on top of said arms, a slice extending across between said side plates at the top thereof, means for moving said slice horizontally relative to 25 the end of said V-shaped member, means for moving said slice vertically in spaced relation above said suction roll, and means for moving said arms about their pivot points to rotate the arcuate member about its pivot point away from the 30 suction roll. 35

4. In a paper machine, a pair of side frame plates, a feed box formed between said plates, an arcuate member pivoted above said feed box, a suction roll rotatably mounted in front of said 40 arcuate member, said side plates, suction roll and arcuate member together forming a passageway for stock from said feed box, a V-shaped member secured to the end of said arcuate member, rods pivotally connected to the end of said V-shaped 45 member, a pair of arms pivoted on the outside of said side plates, a member slidably mounted on the top of said arms for supporting said rods, openings formed through said side plates above said V-shaped member, drain conduits communicating with said openings, a slice extending between said frame plates in front of said V-shaped plate, means for moving said slice relative to 50 said frame plates, and means for regulating the flow of stock from said passageways behind said 55 slice.

5. A wet end for paper making machines comprising a pair of spaced vertical plates, a feed box mounted between said plates, a slice slidably carried by the tops of said plates extending across the space between said plates, means for sliding said slice in a horizontal direction along said plates, means for raising and lowering said slice relative to said plates, arms carried on the sides of said plates having tracks formed in the ends thereof, members slidable in said tracks, a beam extending across the space between said plates secured at its ends to said members, an arcuate plate pivotally mounted on top of the feed box between the plates, means carried by said beam 60 on top of the plates for moving said arcuate plate about its pivot and means for swinging said arms relative to said side plates for moving the members supported thereon in an open position for 65 inspection. 70 75

6. A wet end for paper making machines comprising a pair of spaced vertical walls, an arcuate plate between said walls and pivotally mounted at its lower end, a perforate roll extending longitudinally in spaced relation in front of said arcuate plate, a forming wire disposed around the roll and defining with the plate an arcuate passageway for a pond of stock, a stock inlet for delivering a flow of stock upwardly into the bottom of said passageway, arms pivoted to said walls, means carried by said arms engaging the free end of the arcuate plate and means for swinging said arms about their pivots to move the arcuate plate about its pivot.
5. In a paper making machine including a pair of spaced opposed vertical walls, an arcuate plate pivotally mounted at its lower end between said walls, arms pivotally mounted on the outsides of said walls, means carried by said arms supporting the free end of said arcuate plate and means for swinging said arms about their pivot points to adjust the position of said plate between 10 said walls.

EARL E. BERRY.
